UNITED STATES PATENT OFFICE.

JOSEPH G. BOLTE, OF DAVENPORT, IOWA.

DERRICK.

1,412,159.

Specification of Letters Patent. Patented Apr. 11, 1922.

Application filed May 7, 1920, Serial No. 379,640. Renewed December 17, 1921. Serial No. 523,249.

To all whom it may concern:

Be it known that I, JOSEPH G. BOLTE, a citizen of the United States, residing at Davenport, in the county of Scott and State 5 of Iowa, have invented a new and useful Derrick Machine, of which the following is a specification.

My invention relates to derricks in which rotatable cranes are used, and which are 10 used to elevate bodies by means of a cable operating through a jib secured upon its top.

The objects of my improvement are to provide a portable derrick capable of use in connection with power driven vehicles and to 15 provide a crane which will move bodies without grasping them and capable of delivering them from the side of the derrick to a receptacle provided at either side, of varying 20 heights as desired.

I attain these objects by the mechanism illustrated in the accompanying drawings, in which:

Figure 1 is a plan view of derrick, attached to an ordinary tractor.

Figs. 2 and 3 are respectively front and side elevations of the derrick detached.

Figs. 4 and 5 are respectively side and front elevations of the derrick specifically 30 disclosing the operating sleeve and attachments.

Fig. 6 is a sectional side view disclosing the mechanism for releasing and engaging the carrying arm of the crane.

Fig. 7 is a cross section of the derrick disclosing the sleeve guide groove.

Figs. 8 and 9 are respectively plan view and side elevations of the jib.

Figs. 10 and 11 are respectively plan view 40 and side elevations of the stop collar.

Figs. 12 and 13 are respectively the front and side elevations of the deflector.

Figs. 14 and 15 are respectively plan view and side elevations of the shoe.

Figs. 16 and 17 are respectively plan view 45 and side elevation of the operating sleeve.

Figs. 18 and 19 are respectively plan view and side elevations of the jib crane.

Figs. 20 and 21 are respectively plan view 50 and side elevations of the carrying arm release trigger.

Similar numerals refer to similar parts throughout the several views.

The upright post shown as 1 constitutes 55 the mast upon which the various mechanism of my invention is operated.

Mast 1 is provided at its bottom end with a shoe attachment 7, secured thereto by screw thread or other suitable means, which shoe 7 is constructed in boat form as shown in Figs. 3, 14 and 15, to facilitate its sliding upon the floor of operation, and constitutes the base, said mast 1 is provided at its top end with a jib 3, secured thereto by screw thread or other suitable means, for the purpose of providing in connection with shoe 7 of lug means 3^a and 7^a for the purpose of attaching guy rods 5 and 6 for holding the mast 1 in upright or working position.

Mast 1 is further provided intermediate 70 shoe 7 and jib 3 with a sliding sleeve member 2 loosely mounted thereon and the sleeve member 2 also is provided with a rotating jib crane device 4 which jib crane device 4 is secured at one of its ends upon mast 2 by means of band 4^a formed in the end of said jib crane 4 passing around said sleeve 2 by means of which jib crane 4, when sleeve member 2 may be slidingly raised and lowered upon mast 1.

When the sleeve member 2 is caused to slide upward and downward upon said mast 1, it is retained in uniform position and prevented from turning upon mast one by means of a pivot bolt-head 13 which passes 85 through hole 2^a in sleeve 2 engaging in a groove 1^a provided in and extending lengthwise of the side of mast 1.

Between jib 3 and sleeve 2 is a movable 90 stop collar 9, fitted around mast 1 and secured thereon by set screw means for the purpose of limiting the upward vibratory movements of sleeve 2, and on one side are provided with a pair of uniformly spreading, outwardly disposed angulate grooves, 9^b, having between them a conformable arch-like boss, for the purpose of guiding the deflector 12 in its upward movements.

The jib crane 4 is composed of a ring head 4^a at one end on the side of which it has a bifurcated crane arm, 4^b provided with holes 100 appositely arranged at their ends for the purpose of having mounted between them carrying arm 10, and release trigger 15.

The jib crane 4 is also provided upon its top in front of band 4^a with an upright lug 4^a which upright lug 4^a is provided on its upper end with a hole for securing cable 8 therein.

On one side of sleeve 2 is provided a 110 groove 2^b, the lower part 2^a of which is parallel to the line of the sleeve 2 extending

from its bottom end upward approximately one-third its length, from which point the said groove broadens into a diamond form dimensioned lengthwise of sleeve 2, having 5 extending outward and upwardly from the center line thereof, a pair of grooves 2^a of width similar to groove 2^a terminating in slots 2^e formed in either side of sleeve 2.

At the top end of the diamond groove 2^a 10 is a hole 2^f in sleeve 2 through which is inserted the bifurcated pivot bolt 13^a of the deflector 12 shown as Fig. 13.

Deflector 12 is an oblong bar having a spear head point 12^c at its lower end, and in 15 its middle, hole means not shown for attaching a bifurcated pivot bolt 13^a by pin means 13^b thereto, and above its middle an outwardly flanged offset 12^a and at its top end an inwardly directed flange extension 12^b 20 intended to perform the office of a lock when operating in slots 9^b of the stop collar 9.

The deflector 12 is also formed with its respective ends above and below pivot bolt connection 13^b, outwardly bent, for the purpose of giving the same ratchet working room when the same operates with its connections, for the purpose of allowing flange extension 12^b to have an inward and outward motion when operating in and out of 30 slot 9^b in the operation of the machine.

When the deflector 12 is attached by the bifurcated pivot bolt 13^a means upon sleeve 2, the spear head 12^c fits loosely but conformably within the lower half of diamond 35 groove 2^a, the shank of deflector 12, operating pendulum like within the upper half of diamond groove 2^a as the deflector is moved from side to side to admit the upward turning movement of jib crane 4, as 40 the same is drawn upward by cable 8, and in such action the nose 15^c of release trigger 15 running in groove 2^a on coming in contact with spear head 12^c is deflected into lateral groove 2^b and thereby jib crane 4, 45 as the same is drawn upward by cable 8, is caused to turn to the right or left upon sleeve 2 as the operator, by the setting of stop collar 9, for operating has determined.

The spear head 12^c of deflector 12 is 50 provided with a blunt point so that jib crane 4, in being elevated by cable 8 in passing up groove 2^a nose 15^c of trigger 15, engages the blunt point of spear head 12^c thereby 55 simultaneously carrying sleeve 2 and jib crane 4 upward upon mast 1, until the flanged extension 12^b of deflector 12 is engaged by the slot 9^b of stop collar 9 thereby causing the top end of deflector 12 to be 60 pressed outward and the spear head 12^c to be pressed inwardly against the inner part of diamond groove 2^a, and the deflector 12 to turn upon pivot bolt 13^a deflecting spear head 12^c to one side and allowing jib crane 4 to pass upward over the head 12^c 65 of deflector 12 and nose 15^c of release trig-

ger 15 to pass up groove 2^b until nose 15^c of release trigger 15 engages in oblong slot 2^e provided in the wall of sleeve 2 at the termination of groove 2^b, when the said release trigger 15 rotates upon pin not shown 70 inserted in hole 4^c of jib crane 4, thereby releasing carrying arm 10 which previously thereto had been held in rigid position by minor lug 15^b of trigger 15, thus allowing the outward end of carrying arm 10 to fall 75 and release its load. As jib crane 4 in its upward movement passes over pivot bolt 13^a it presses the upper portion of deflector 12 inwardly, causing flanged extension 12^b to engage stop collar 9, thereby locking sleeve 80 2 upon stop collar 9, and simultaneously the bottom portion of deflector 12 is by this action forced outward.

In construction the inward end 10^a of carrying arm 10 is made heavier than its opposite end, so that on the load being released by gravity by the release of trigger 15, the carrying arm falls back into position falling upon 15^a of trigger 15, approximately as shown in Fig. 6, whereupon by 85 slackening cable 8, the jib crane 4 moves by gravity downward by which movement the nose 15^c of trigger 15 engaged in slot 2^e by contact with the bottom edge of slot 2^e, causes trigger 15 to revolve, thereby causing 90 minor lug 15^b to lock carrying arm 10, in its rigid position. In the further passage of jib crane 4 by gravity downward, it presses upon the lower of deflector 12 thereby by gravity forcing the upper portion of 95 deflector 12 outward, forcing deflector 12, outward until the same releases its hold upon stop collar 9 and the sleeve 2 by gravity slides downward upon mast 1, carrying jib crane 4 with it, when the machine is in position for reloading.

Jib 3 is provided with a hood portion 3^b in which is mounted a wide grooved pulley 14 upon axle 3, the wheel 14 being for the purpose of facilitating the movement of 100 cable 8, by which the mechanism is raised and lowered, and hood 3^b is for the purpose of retaining the cable 8 upon pulley 14 in operation.

My machine when constructed is attached 115 to an ordinary power driven vehicle, and pushed forward upon the shoe 7, in which mast 1 is mounted, thus driving the fixed carrying arm into hay, manure, or any substance desired to be lifted, and when a load 120 is thus secured the same is elevated and moved to and deposited at the desired place by means of the cable 8 and the mechanism described, and by the same process, moved from one position to another.

I claim:

1. In a derrick a mast having a jib top provided with hood and pulley means; a linearly grooved side; a shoe means attached to the bottom end of the mast; movable 130

sleeve means mounted on a mast, means for preventing the said sleeve from revolving on said mast; jib crane means having a bifurcated end and a ring collar, a carrying 5 arm, a trigger and a carrying lug, the whole mounted on said sleeve; means for hoisting a jib crane upon a mast; means for rotating a jib crane upon a mast; means for holding a jib crane in hoisted position upon 10 a mast, other means for releasing a jib crane and sleeve when secured at the top of a jib thereby permitting them to drop; deflector means provided upon the sleeve of a derrick for directing the turning of a jib 15 crane upon a sleeve attachment of a derrick; trigger means in connection with a carrying arm provided in a jib crane for holding and releasing a carrying arm when operating a jib crane, a stop collar having 20 grooves and a boss provided upon a mast for the purpose of controlling the operations of a jib crane; a deflector having a pivot bolt; a spear headed end, a flanged end, hole means in its center for attachment 25 of pivot bolt means, each end of the deflector outwardly bent from its center, one of said ends having an outwardly right-angularly bent offset, said end also having a right-angularly inwardly bent flange, a 30 pivot bolt having a perforated, bifurcated end for attachment to a deflector its other end having an enlarged round head, suited for insertion in the linear groove of a mast; a sleeve member mounted on a mast, the 35 sleeve member having a linear groove upon its side at one end, a diamond groove connected therewith, the diamond groove having a central perforation, a pair of side grooves extending from the lateral portions 40 of the diamond groove upwardly disposed around said sleeve member, a pair of oblong slot perforations lineally disposed in the sides of said sleeve connectedly attached at the upper ends of said upwardly disposed 45 side grooves; the whole forming a derrick and for the purposes specified.

2. I claim in a derrick, a mast having a linear groove in its outside, a hooded jib having a pulley mounted upon an axle there- 50 in by boxing means provided in the sides of the hood the jib secured stationarily upon the top of said mast; ear means provided with an eyehole in the rear of the jib for guy rod attachments, the bottom of said 55 mast stationarily anchored in an oblong shoe, the shoe having a rounded boat form bottom and dimensioned suitably larger than the diameter of the mast, ear means provided with an eyehole in the top rear portion of said shoe for guy rod attach- 60

ments; sleeve means mounted loosely upon said mast capable of sliding upward and downward thereon, hole means provided in the side of said sleeve, a bifurcated pointed pivot bolt having a head conformable to the groove in the mast inserted from the inside of said sleeve outward through the hole in the side of said sleeve in such manner that the head of said pivot bolt engages in the groove of said mast groove means in 70 the outward surface of sleeve about the hole in said sleeve dimensioned to admit a deflector loosely mounted therein; a deflector secured by any ordinary means between the bifurcations of the end of a pivot bolt protruding through the wall of a sleeve, operating in a suitably shaped groove formed in the outside of the wall of said sleeve, its top and bottom ends bent directioned outwardly from said pivot fastening, its top 80 end extending upward beyond said sleeve; a jib crane having an end ring provided at one end, and a pair of bifurcated arms at its other end, also having ear means on its upper side, containing an eyehole for attachment of a cable thereto, said jib crane mounted loosely by its end ring upon a sleeve member of a derrick and held thereon by flange means in one end of said sleeve and by the shoe means provided at the end 85 of a mast at the other, said jib crane and sleeve capable of being hoisted on said mast by cable means operating through a pulley mounted in a jib secured on the top of said mast, said jib crane also provided between 90 the bifurcations of its outward end with carrying arm means and means for tripping and reengaging it in said jib crane; deflector means provided connectedly with said sleeve member in such manner as to operate 95 upon a trigger provided in the jib crane member conjunctively with a stop collar member arranged upon a mast; rotating trigger means provided in the bifurcations of the jib crane adjacent to said sleeve in 100 conjunction with grooves and slots in said sleeve also in conjunction with a carrying member mounted between the bifurcated arm members of a jib crane secured upon a sleeve, the whole forming a derrick capable 105 of being operated by a power driven vehicle and for the purposes specified.

Dated at Davenport, Iowa, this 30th day of April, A. D. 1920.

JOSEPH G. BOLTE.
